ELECTRIC SIGNAL SYSTEM

Clyde C. Farmer, Pittsburgh, and Thomas H. Thomas, Edgewood, Pa., assignors to The Westinghouse Air Brake Company, Wilmerding, Pa., a corporation of Pennsylvania

Application August 8, 1927, Serial No. 211,348

4 Claims. (Cl. 177—352)

This invention relates to signal systems, and more particularly to an electric signal system adapted for use on railway trains.

An object of our invention is to provide an electric train signal system by the use of which a trainman may signal the engineman from any car of a train and by which the engineman's reply signal may be received by the trainman only at the station from which the signal was sent by the trainman or at any other station or stations the trainman may choose.

Another object of the invention is to provide an electric train signal system for railway trains, in which the sources of electric current on the cars of the train are connected to ground only when the system is being used in signalling.

In the accompanying drawings, Fig. 1 is a diagrammatic view of an electric signal system embodying the invention and illustrating the engineman's switch in one position; and Figs. 2 and 3 are diagrammatic sectional views illustrating the engineman's switch in two other positions.

As illustrated in the accompanying drawings the locomotive or controlled car of a train may be provided with an electric battery 1 or any other desired source of electric current, a signal indicating device such as a buzzer 2 and an engineman's switch 3 comprising a rotatable member 4 which is provided with a contact 5 adapted in one position to electrically connect terminal contacts 6 and 7 which are connected to ground at 8 and to one terminal of the buzzer 2, respectively, and in another position to electrically connect terminal contacts 9 and 10, which are connected to the positive terminal of the battery 1 and to a train wire 11, respectively. The negative terminal of the battery 1 is connected to ground at 12. The train wire 11 is connected to the other terminal of the buzzer 2.

Each of the cars of a train may be provided with an electric battery 12 or any other suitable source of electric current, a signal indicating device such as a buzzer 13, a switch device 14 and a jack device 15.

The switch device 14 comprises a casing 16 containing a sliding contact member 17, which member is provided with an operating stem 18 adapted to be operated, in one direction, by a lever 19 having operating arms 20 and 21, each having an operating cord 22 attached thereto. This lever 19 is adapted to fulcrum around pins 23 and 24 which are so disposed and mounted in the casing

16, that when the arm 20 is operated the lever turns about the pin 23 and when the arm 21 is operated the lever turns about the pin 24 and in either case the lever depresses the stem 18 and the contact member 17, rotative movement of the member being prevented by a pin mounted in the casing engaging in a slot formed in the member.

The member 17 is provided with contacts 25, 26

and 27 and is normally maintained in the position shown in the drawings by the action of a spring 28. When the member 17 is moved a predetermined distance by the lever 19, the end of the member will engage and stop against a stop formed on a plug 29 having screw-threaded connection with the casing. When the member 17 is in this position the contact 25 connects terminal contacts 30 and 31 in the casing, the contact 30 being connected with the positive terminal of the battery 12 and the contact 31 being connected with one terminal of the signal indicating device 13 and the contact 27 connects terminal contacts 32 and 33, the contact 32 being connected to ground at 34 and the contact 33 being connected with the negative terminal of the battery 12. When the member 17 is in its normal position, as shown in the drawings, the contact 26 connects terminal contacts 35 and 36, the contact 35 being connected with a tine 37 of the jack 15 and the contact 37 being connected to ground at 34.

The jack 15 is also provided with a tine 38 which is connected with the wire which connects the terminal contact 31 and the buzzer 13. The tines 37 and 38 of the jack are normally disconnected but are adapted to be connected by the insertion of a plug 39 between them.

Assuming the several parts of the signal system to be in the positions as shown in Fig. 1 of the drawings, and the trainman desires to signal the engineman, the trainman pulls the cord 22, which causes the lever 19 to operate to depress the stem 18 and contact member 17 to the position in which the contact 25 connects the terminal contacts 30 and 31, and the contact member 27 connects the contact terminals 32 and 33. With the engineman's switch in the position shown in the drawings an electric circuit is completed from ground 34, contact 27, battery 12, contact 25, buzzer 13, train wire 11, buzzer 2 and contact 5 of the engineman's switch, to ground 8, and both buzzers 2 and 13 will operate. If the trainman desires he may hold the contact member 17 depressed, which causes the buzzers 2 and 13 to operate until such time as the engineman, by the rotation of the contact member 4 of his switch causes the contact 5 thereof to open and close the circuit, thus controlling the operation of both buzzers. It will thus be noted that with this circuit, the trainman and the engineman may signal back and forth to each other as many times as necessary.

With the several parts of the signal system in the positions as shown in Fig. 1 of the drawings, and the trainman desires the system to be in readiness that he might receive, at his station on the train, any signal which might be initiated by the engineman, he inserts the plug 39 between the tines 37 and 38 of the jack 15, thus causing one terminal of the buzzer 13 to be

connected through the jack and contact 26 to ground 34. Now, if the engineman wishes to signal the trainman, he rotates the member 4 to the position shown in Fig. 3 of the drawings, 5 in which position, the contact 5 connects the terminal contacts 9 and 10, which completes a circuit from ground 8 through battery 1, contact 5, train wire 11, buzzer 13, jack 15 and contact 26 to ground 34. Should the trainman desire the 10 engineman's signal to sound in all of the cars of the train, he inserts a plug 39 in each of the jacks 15.

It will here be noted that the trainman's switch, in its normal position as shown in the drawings, 15 maintains both terminals of the battery 12 disconnected from ground and from the remainder of the signal circuit, thus reducing to a minimum the possibilities of short circuiting the battery. The only time this battery is connected to ground 20 is when the trainman operates his switch to signal the engineman, i. e., when the contact member 17 is in its depressed position.

Having now described our invention, what we 25 claim as new and desire to secure by Letters Patent, is:—

1. In a train signal system, a train signal circuit system including a train wire, a source of current on the power vehicle of the train having one of its terminals connected to ground, a signal 30 indicating device on the power vehicle having one of its terminals connected to said train wire, a switch device on said vehicle for connecting the other terminal of said source to said train wire and for connecting the other terminal 35 of said signal indicating device to ground, said switch device having an operating zone in which the connection from said train wire to said other terminal of said source of current may be opened and closed while the connection from the signal indicating device to ground remains open, a signal 40 indicating device on each car of the train having one terminal connected to said train wire, a source of current on each car, a normally open switch device on each car adapted to be closed 45 to connect the other terminal of the local car signal indicating device to ground, another switch device on each car of the train operable to connect one terminal of a local source of current to said other terminal of the local signal indicating 50 device and consequently to the train wire and to connect the other terminal of the local source of current to ground.

2. In an electric signal system for a train, a plurality of normally open signal circuits, a train 55 wire constituting a portion of each of said circuits, a signal indicating device included in each circuit and having one terminal connected to the train wire, a source of electric current for said circuits having one terminal connected to ground and normally disconnected from said circuits, a normally open switch included in each 60 of said circuits operable to connect the other terminal of a local signal indicating device and consequently the train wire to ground, another 65 normally open circuit which includes said train wire, a signal indicating device included in said circuit having one of its terminals connected to the train wire, a plurality of sources of electric current for the last mentioned circuit normally 70 disconnected from the circuit, switch means for at one time connecting the train wire to the other terminal of said source of current and for at another time connecting the other terminal of the second mentioned signal indicating device to 75 ground, said switch means having an operating

zone in which the connection from said train wire to said source may be opened and closed while the connection from the signal indicating device to ground remains open, and when so operated opening and closing the circuit through the first mentioned source of current, train wire and signal indicating device which is connected to ground by one of the first mentioned switches, and said switch means when in position closing the connection from the second mentioned signal indicating device to ground maintaining the connection from the train wire to the first mentioned source of current open, a switch device included in each of said plurality of circuits operable to connect one terminal of the local source of current to ground and the other terminal to the train wire, said switch device being operable to open and close the connections from the local source of current to the train wire to control the operation of the second mentioned signal indicating device when said switch means is in position to connect the second mentioned signal indicating device to ground.

3. In a train signal system, a signal circuit system including a train wire, a source of electric current on the power vehicle of the train, said source of current having one terminal connected to ground, a source of electric current on each car of the train, a signal indicating device on each car and having one terminal connected to the train wire, normally open switch devices on the cars of the train adapted to be selectively closed to connect the other terminal of the local car signal device to ground, switch means on the power vehicle having an operating zone in which a connection from the other terminal of the source of current on the power vehicle to the train wire may be opened and closed to control the operation of the local car signal indicating device which is connected to ground by the local switch device and having a position for connecting the other terminal of the signal indicating device on the power vehicle to ground while the connection from the train wire to said source of current remains open, and switch devices on 110 said cars selectively operable to connect one terminal of a local source of current to ground and the other terminal to the other terminal of the local car signal device and consequently to the train wire and operable to open and close the circuit through said local source of current train wire and signal indicating device on the power vehicle to cause the signal indicating device to operate when said switch means is in position connecting the signal indicating device to ground. 130

4. In a train signal system, a train wire, a signal device on the power vehicle of the train connected to said wire, a source of current on said vehicle connected to ground, a switch device on said vehicle for connecting said source to said wire and for connecting said signal device to ground, said switch device having an operating zone in which the connection from said wire to said source may be opened and closed while the connection from the signal device to ground remains open, a signal device on each car of the train, each connected to said wire, a source of current on each car, a switch device on each car having one position for connecting said local source of current to ground and to said train wire and another position for connecting said train wire to ground, while the connection from the local source to the train wire remains open. 140
